UNITED STATES PATENT OFFICE

159,340

COMBINATION CAP AND WICK FOUNTAIN
BRUSH

Morris Huzarsky, New York, N. Y., assignor of one-sixth to Arnold Bank, New York, N. Y.

Application January 13, 1948, Serial No. 143,690

Term of patent 7 years

(Cl. D74—10)

To all whom it may concern:

Be it known that I, Morris Huzarsky, a citizen of the United States, residing at New York, in the county and State of New York, have invented a new, original, and ornamental Design for a Combination Cap and Wick Fountain Brush, of which the following is a specification, reference being made to the accompanying drawings, forming a part thereof.

In the drawings:

Fig. 1 is a side view of a combination cap and wick fountain brush showing my new design;

Fig. 2 is an end view thereof;

Fig. 3 is a top view thereof; and

Fig. 4 is a bottom view thereof.

I claim:

The ornamental design for a combination cap and wick fountain brush, as shown.

MORRIS HUZARSKY.
